WEB PRINTING MACHINE

Filed Nov. 27, 1928

UNITED STATES PATENT OFFICE

HARRY V. BALL, OF CONCORD, MASSACHUSETTS, ASSIGNOR TO R. HOE & CO., INC., OF NEW YORK, N. Y., A CORPORATION OF NEW YORK

WEB-PRINTING MACHINE

Application filed November 27, 1928. Serial No. 322,198.

This invention pertains to improvements in web printing machines of the class used for printing newspapers and similar products. In my copending application Serial No. 267,330, filed April 4, 1928, I disclose a multi-unit printing machine in which the press units are arranged with their two printing couples in superposed relation one to the other, in narrow framing thereby providing a press unit of unusually small dimensions longitudinally of the machine, yet still retaining most of the desirable features of the machines then in use.

The invention herein disclosed constitutes a further improvement, with the object of providing a press unit in which one of the printing couples is superposed over the other couple in narrow framing and in which all of the printing cylinders are accessible from one floor level.

Another object is to provide a press unit having a driving mechanism of improved design.

It is also an object of the invention to provide a press unit of generally improved construction, whereby the device will be simple, durable and inexpensive in construction as well as convenient, practical, serviceable and efficient in its use.

With the foregoing and other objects in view, which will appear as the description proceeds, the invention resides in the combination and arrangement of parts, and in the details of construction hereinafter described and claimed, it being understood that various changes in the precise embodiment of the invention herein disclosed may be made within the scope of what is claimed without departing from the spirit of the invention.

The drawing which forms a part of this specification shows a side view in outline of a portion of a multi-unit web printing machine. Two press units and a folder are shown for the purpose of illustrating the invention.

A substructure indicated at 11, forms a support for a base frame 12. A main drive shaft 13, is supported in bearings 14 which are secured to the base frame 12. The press units which are indicated generally at P 1 and P 2 print on webs drawn from web rolls located

on a lower floor below the portion of the sub-structure shown. The webs indicated at W 1 and W 2 are fed up through the press units to overhead guide rollers 15 and 16, to compensating rollers 17, and thence to the folder 55 F which is of well known construction.

The press units each include two printing couples supported in suitable framing 18. The first couple comprises an impression cylinder 19 and a plate or form cylinder 20 which is inked by suitable mechanism indicated at 21. The second couple which is located in superposed relation to the first couple comprises an impression cylinder 22 and a plate or form cylinder 23, having inking 60 mechanism 24.

The floor of the press room is shown in section at 25 and it will be noted that the construction of the units and their location with respect to the floor level, permit convenient access to all of the form and impression cylinders, as they are so placed that the operator can work on them when standing on the floor. 70

In the preferred arrangement, unit drive 75 shafts 26 are obliquely supported in bearings 27, and have secured thereto bevel gears 28 which mesh with bevel gears 29 secured to the main drive shaft 13. Miter gears 30 and 31 are also secured to the unit drive shaft 80 26 and mesh with similar gears secured to the impression cylinders 19 and 22 respectively. The corresponding cylinders of both printing couples of each unit are thus driven through equivalent connections, this arrangement being conducive to the best results. 85

The web W 1 or W 2 is led to the guide roller 32, between the printing couple 19 and 20 where it is printed on one side, around the guide rollers 33 and 34, through the printing couple 22 and 23, where it is printed on the other side, and thence to the folder F as previously described. 90

What I claim is:

1. In a multi-unit newspaper printing machine, a base frame with bearings supporting a main drive shaft, and a plurality of printing units each including two printing couples arranged in superposed relation one to the other with the printing cylinders of 100

- each couple in substantially horizontal alignment, with the plate cylinders of both printing couples accessible from one floor level with the plate cylinder of each printing couple in substantially vertical alignment with the impression cylinder of the other couple and with a unit drive shaft for each printing unit geared to one cylinder of each printing couple and to the main drive shaft.
2. In a multi-unit newspaper printing machine, a base frame with bearings supporting a main drive shaft, a plurality of printing units each including two printing couples arranged in superposed relation one to the other with the form cylinder of each printing couple in substantially horizontal alignment with its impression cylinder and positioned over or under the impression cylinder of the other couple and with the plate cylinder of each printing couple within reach of an operator standing on the floor, and an obliquely supported unit drive shaft geared to corresponding cylinders of each printing couple and to the main drive shaft.
3. In a multi-unit web printing machine, a base frame with bearings supporting a main drive shaft, a plurality of printing units, a folder, web guides leading webs from below the base frame, up through the printing units, and web guides above the units leading the webs to the folder; said printing units each including two printing couples arranged in superposed relation one to the other in narrow framing, with all their printing cylinders accessible from one floor level, and with the form cylinder of each printing couple in substantially vertical alignment with the impression cylinder of the other couple.
4. In a multi-unit web printing machine, a base frame with bearings supporting a main drive shaft, a plurality of printing units, a folder, web guides leading webs from below the base frame, up through the printing units, and web guides above the units leading the webs to the folder, said printing units each including two printing couples arranged in superposed relation one to the other in narrow framing, with all their printing cylinders accessible from one floor level, with the form cylinder of each printing couple in substantially vertical alignment with the impression cylinder of the other couple and obliquely supported unit drive shafts one for each printing unit geared to corresponding cylinders of each printing couple and to the main drive shaft.

In testimony whereof, I affix my signature.
HARRY V. BALL.
